5,676,580 10/1997 Farrar .
5,732,947 3/1998 Noack .
5,833,512 11/1998 Nicola .
5,868,429 2/1999 Raymond et al. .

(75) Inventor: **Bruce Fong**, Kowloon Bay (HK)
(73) Assignee: **Sleep Innovations Inc.**, West Long Branch, NJ (US)

(**) Term: **14 Years**

(21) Appl. No.: **29/136,881**

* cited by examiner

(22) Filed: **Feb. 8, 2001**

Primary Examiner—Sandra L. Morris
(74) Attorney, Agent, or Firm—Ezra Sutton

(51) LOC (7) Cl. **21-01**

CLAIM

(52) U.S. Cl. **D21/335**; D21/342; D21/349;

The ornamental design for a foldable game board with fastener for checkers, as shown and described.

D21/366

(58) **Field of Search** D21/334, 335, D21/342–345, 348, 349, 363, 366; 273/236, 258, 260, 271, 281, 282.1, 282.2, 285, 288, 291

DESCRIPTION

FIG. 1 is a perspective view showing the foldable game board with fastener for checkers in a folded configuration embodying my new design;

FIG. 2 is a perspective view showing the foldable game board with fastener for checkers in a open configuration embodying my new design;

FIG. 3 is a front view of the open configuration thereof;

FIG. 4 is a back view of the open configuration thereof;

FIG. 5 is a right side view of the open configuration thereof;

FIG. 6 is a left side view of the open configuration thereof;

and,

FIG. 8 is a rear end view of the open configuration thereof.
